UNITED STATES PATENT OFFICE.

OTTO FRANK REINEN, OF LOS ANGELES, CALIFORNIA.

MACHINE FOR CUTTING OUT MICA BETWEEN SEGMENTS IN COMMUTATORS.

No. 906,160.

Specification of Letters Patent.

Patented Dec. 8, 1908.

Application filed September 30, 1907. Serial No. 395,109.

To all whom it may concern:

Be it known that I, OTTO FRANK REINEN, a citizen of the United States, residing at Los Angeles, county of Los Angeles, State 5 of California, have invented a Machine for Cutting Out Mica between Segments in Commutators, of which the following is a specification.

This invention relates to a machine designed to be used in a repair shop for cutting out mica between the segments of the commutator of an armature after truing the same, thus making a good contact between the brushes and commutator. Heretofore 10 the mica has been trimmed out from between the segments of the commutator by hand, usually with a hack-saw, which is very laborious and consumes much time, and the objects of the present invention are to 15 provide a machine whereby this is accomplished in a perfect manner and with great rapidity.

The accompanying drawings illustrate the invention and referring thereto:—Figure 1 20 is a side elevation of the machine, showing an armature with commutator in position in the machine ready for the operation. Fig. 2 is a section on line x^2-x^2 Fig. 1. Fig. 3 is a section on line x^3-x^3 Fig. 1. Fig. 4 is an enlarged plan view in detail of 25 a portion of the machine, illustrating the cutter, its arbor and guide, and the commutator end of the armature.

1 designates the armature having commu- 30 tator 2, the latter having segments 3 spaced apart by mica insulation 4.

5 is the armature shaft. The armature is supported by a truck comprising a frame 6 mounted on axles 7 equipped with wheels 8. 35 Pillow blocks 9 extend up from the frame 6 and their upper ends are concaved, and the shaft 5 of the armature rests in the ends of the pillow blocks 9.

10 is a tongue connected to the truck for 40 moving the truck.

11 designates the bed plate of the machine, upon which rests a carrier frame 12, the latter being swiveled at 13 to the bed plate 11 so that it may be adjusted angularly on the 45 bed plate. Projecting up from each end of the carrier frame 12 is a standard 14. One of the standards is adjustable on the frame as by means of perforations 12', by means of which armatures of different lengths are 50 supported in position for being operated upon. At one end of the bed plate 11 is a

pair of brackets 15 arranged on opposite sides of the carrier frame, and an adjusting screw 16 is threaded in each bracket 15 and bears against the adjacent standard 14, each 55 adjusting screw 16 having a hand wheel 17, and the screws 16 may thus be adjusted to swing the carrier frame 12 on its swivel 13 to the required position. A step bracket 18 is arranged on each standard 14, and a slide 60 bar 19 is mounted on each standard 14 to slide vertically thereon, having slots 20 through which bolts 21 pass. Each slide bar 19 has a lug 22 in which is journaled a vertical shaft 23, the lower end of shaft 23 being mounted in a step bearing in the step bracket 18, and the lower end of the shaft 23 is provided with a screw 24 which engages with a stud 25 projecting from the slide bar 19. The upper end of shaft 23 is provided 65 with a hand wheel 26 whereby the screw 24 may be turned to adjust the slide bar 19 vertically with respect to its standard 14. Threaded in each slide bar 19 is a center 70 75 80 85 90 95 100 105 110 115 120 125 130 135 140 145 150 155 160 165 170 175 180 185 190 195 200 205 210 215 220 225 230 235 240 245 250 255 260 265 270 10015 10020 10025 10030 10035 10040 10045 10050 10055 10060 10065 10070 10075 10080 10085 10090 10095 10100 10105 10110 10115 10120 10125 10130 10135 10140 10145 10150 1015

engagement with the centered ends of the armature shaft 5, which operation is readily accomplished even though the truck does not stand in position such that the armature 5 shaft is in perfect alinement, as by operating adjusting screws 16 the carrier frame 12 may be adjusted angularly to swing the centers 27 in a horizontal plane alining with armature shaft centers 5, and for vertical alinement 10 the centers 27 may be adjusted up or down vertically by means of the screws 24. Thus, while the armature rests on the pillow blocks 9 and its weight is supported thereby, the centers 27 may readily be engaged with the 15 ends of the armature shaft, and after that has been accomplished the slide bars 19 are adjusted up by operating screws 24 so that the weight of the armature is borne by the centers 27. Then the carrier frame 12 is 20 adjusted to bring the armature shaft 5 into parallelism with the ways 32 of table 31, so that as the cutter is moved along it will, provided the commutator segments are in perfect alinement with the shaft, traverse the 25 slots without cutting into the commutator segments. Quite frequently, however, the commutator segments 3 will not be in perfect parallelism with the axis of shaft 5, but slightly skewed, and when such is the 30 case the carrier frame 12 is adjusted angularly the necessary slight amount to bring the slot between the commutator segments into perfect parallelism with ways 32, as the essential adjustment to be made is that of 35 securing parallelism between the slots of commutator segments and ways 32. After such adjustment has been effected, the proper elevation of the commutator is secured by operating screws 24 and the commutator is 40 thereby so adjusted that the cutting depth of the cutter 45 will be the required amount. These adjustments having been made, then by operating hand lever 39, the yoke which carries arbor 35 is advanced to cause the 45 cutter 45 to traverse the slot between two adjacent commutator segments and trim out the required slight amount of mica between the segments. It is obvious that the cutter will traverse the commutator very quickly, 50 and after one traverse the lever 39 is retracted and the armature 5 is turned on its centers 27 to bring the next slot into position and the lever 39 is again moved forward to make the next cutting, and so on until the 55 entire number of mica slots have been trimmed. After completing the job, the armature is then lowered so that its shaft 5 again rests in the pillow blocks 9, the left hand standard 14 is again unbolted and the truck supporting the armature is then withdrawn from the machine. 60

What I claim is:—

1. In a machine for trimming mica in commutators, a cutter reciprocably mounted 65 so as to be movable in a straight line, a re-

movable commutator support, means for engaging with the commutator and removing it from its support, and means for adjusting said last mentioned supporting means vertically and laterally, relatively to the removable support and to the cutter, whereby the commutator may be lifted from its removable support and properly adjusted relatively to the cutter independently of said removable support. 70

2. In a machine for trimming mica in commutators, a cutter reciprocably mounted so as to be movable in a straight line, a wheeled commutator support adapted to be moved relatively toward and from the cutter and to support a commutator while in transit, adjustable means for being moved into engagement with the commutator while upon its support, and adjustable means for engaging with said last mentioned supporting means for removing the commutator from its support and moving it into position relatively to said cutter so as to be acted upon thereby. 75

3. In a machine for trimming mica in commutators, a cutter reciprocably mounted so as to be movable in a straight line, a wheeled truck provided with standards, each having an open support at its upper end for holding a commutator, adjustable means adjacent to the cutter for engaging with the ends of the commutator shaft and lifting the commutator from the truck, and means for moving said last mentioned supporting means so as to move the commutator into proper parallelism relatively to the path of the cutter. 90

4. In a machine for trimming mica in commutators, a cutter reciprocably mounted so as to be movable in a straight line, a 105 wheeled truck provided with two standards for supporting a commutator, two standards adjacent to the cutter, one of which is removable and each is provided with vertically adjustable means for engaging with the commutator shaft and lifting the commutator from the truck standards, and laterally adjustable means for moving the commutator into proper parallelism relatively to the cutter. 110

5. In a machine for trimming mica in armatures, a base provided with a standard, a bracket adjustably secured thereto, a cutter reciprocably mounted on the bracket to move in a straight line, a carrier frame 120 swiveled on said base, a standard at each end of said frame, means at one end for adjusting the frame, and vertically adjustable means on each standard for supporting an armature in position for being operated 125 upon by said cutter. 115

6. In a machine for trimming mica in armatures, a base provided with a standard, a bracket adjustably secured thereto, a cutter reciprocably mounted on the bracket to 130

move in a straight line, a carrier frame swiveled on the base having a standard at each end, oppositely disposed screws at one end of the frame for adjusting it laterally, and 5 vertically adjustable means on each standard for supporting an armature in position for being operated upon by said cutter.

7. In a machine for trimming mica in armatures, a base provided with a standard, 10 a cutter supported by said standard to be moved reciprocably in a straight line, a carrier frame swiveled on the base having a standard at each end, means for moving the frame on its swivel, a step bracket on each 15 standard, a slide bar adjustably mounted on each standard provided with a stud and a perforated bracket, a shaft through said perforation with a wheel on its upper end and having its lower end screw-threaded and seated in the step bracket in position for said 20 threads to engage with said stud, and a supporting center in each bar for holding an armature in position for being operated upon by said cutter.
- 25 8. In a machine for trimming mica in armatures, a base adapted to receive a wheeled truck and provided with a standard, a cutter supported on the standard so as to be moved reciprocably in a straight line, a 30 frame swiveled on said base provided with a standard at each end, each standard being provided with adjustable means for engaging with a commutator, lifting it from the truck and holding it in position to be operated upon by said cutter, and means for adjusting the ends of said frame laterally relatively to the base.
- 35 9. In a machine for trimming mica in armatures, a base provided with a standard, 40 a cutter supported on the standard so as to be

moved reciprocably in a straight line, a frame swiveled on the base, one end of which is bent upwardly to form a standard and the other end is perforated, a standard removably seated in said perforations, means 45 for adjusting said frame laterally relatively to the base, and means adjustably secured to said standards for supporting an armature in position to be operated upon by said cutter.

10. In a machine for trimming mica in armatures, a base provided with a standard, a table adjustably supported by said standard, slotted ways on the table, blocks in said ways, an arbor through said blocks provided 50 with a cutter at one end, a yoke for reciprocably moving the blocks along the ways, a handle connected with the yoke for moving it, and adjustable means connected with the base for holding an armature in position for 55 being operated on by said cutter.

11. In a machine for trimming mica in armatures, a base provided with a standard, a table adjustably supported by said standard, slotted ways and a perforated stud on 60 the table, blocks in said ways, an arbor through said blocks with a cutter on one end, a yoke for reciprocably moving the blocks along the ways, a stem from the yoke through said stud, a handle connected with 65 the stem, and adjustable means on the base for supporting an armature in position for being operated on by said cutter.

In testimony whereof, I have hereunto set my hand at Los Angeles, California, this 75 21st day of September 1907.

OTTO FRANK REINEN.
